E. SCHINSCHOLL

EGG CARTON

Filed Sept. 26, 1924

INVENTOR.

Patented June 7, 1927.

1,631,554

UNITED STATES PATENT OFFICE.

ERICH SCHINSCHOLL, OF CINCINNATI, OHIO.

EGG CARTON.

Application filed September 26, 1924. Serial No. 740,119.

It is the object of my invention to provide an egg carton of novel construction, whereby the eggs are securely held in separated relation in the carton and cushioningly protected; further, to provide novel cushioning means formed in the carton for the individual eggs; and, further, to provide supporting means whereby the egg containing portion of the carton is raised above the 10 table or other object on which the carton may be supported.

The invention will be further readily understood from the following description and claims, and from the drawing, in which 15 latter:

Fig. 1 is a perspective view of my improved device in assembled relation.

Fig. 2 is a longitudinal section of the same, taken on the line 2—2 of Fig. 1; and, 20 Fig. 3 is a cross-section of the same, taken in the plane of the line 3—3 of Fig. 2.

The carton is of the pressed type, being usually formed of pressed strawboard or other fiber board, and formed into containers 25 of cylindrical form, two of which are shown formed side by side, each of the cylindrical portions being arranged to contain in practice a half dozen eggs, so that the carton shall hold one dozen eggs, although other 30 sizes may be made.

The shell of the carton comprises substantially semi-cylindrical portions 12, 13, and 14, 15, arranged to be placed opposite each other for forming the substantially 35 cylindrical egg-containing sections of the shell.

The shell is preferably formed in one piece, the sections in which the semi-cylindrical sections are formed being hinged together by the flexible score 16, so that the 40 halves of the shell may be opened and closed for insertion and removal of the eggs.

The semi-cylindrical portions 12, 13, have the bent portion 17 between them, and the 45 semi-cylindrical portions 14, 15, have the bent portion 18 between them.

Nests 21, 22, are provided for the respective halves of the carton, and comprise sheets of the carton provided with pockets 26, 27, 50 which mate each other in the respective halves of the carton, for receiving the respective halves of the eggs contained therein, and holding the eggs securely in individual pockets and separating the eggs from 55 each other. The pockets 26, 27 are prefer-

ably formed as sectors pressed from the body of the sheet forming the carton.

The longitudinal edges of the sheets are provided with flanges 28, 29, bent therefrom along the scores 30, 31, respectively resting upon the inner peripheries of the respective semi-cylindrical sections 12, 14, of the shell, so as to support the respective nest-halves on the respective shell-halves. The flanges 28, 29, extend at substantially 60 right angles from the respective sheets of the nests and thereby strengthen said nests and preferably extend across the ribs hereinafter described in the substantially semi-cylindrical sections for aiding in strengthening 65 said sections. These flanges may be secured to the semi-cylindrical sections 12, 14, by bands of paste indicated at 32, 33, if desired. The intermediate bent portions 17, 18, of the respective shell-halves 70 preferably find support on said nest-halves, and may, if desired, be pasted to said nest-halves, as indicated at 34, 35, so as to securely connect the ridges of said depressed portions and the nest-halves. 75

The respective shell-halves have indentations 41, 42, formed therein for forming inwardly indented cushion-seats, which register in axial directions with the respective egg-pockets in the carton, and are arranged to be contacted by the respective ends of the eggs in said pockets for cushioning said ends and preventing breakage or cracking of said ends. These indentations are formed up 80 out of the body of the shells. 85

The indentations 41 are shown as individual indentations for individual eggs, and the indentations 42 are shown as extending lengthwise of the shell, to encompass a plurality of eggs, shown as two. These indentations further serve to strengthen the shell 90 and aid in maintaining the shape of the cylindrical shell.

In order to further cushion the eggs and to strengthen the carton, I provide ribs 44 100 extending radially outward from the body of the shell, around the periphery of the shell, so as to support the shell by means of said ribs when the carton is laid upon a table or other similar object for supporting the carton. These ribs raise the body of the carton above the table or supporting object, and thereby raise the eggs away from 105 danger of concussion by contact of the carton with the table or support and cushion 110

the collective eggs in the carton, the eggs being also individually cushioned by the indentations.

I prefer to further strengthen said carton 5 and said ribs by forming ribs 45, 46, parallel with the ribs 44, and at the respective sides of the ribs 44, the ribs 45, 46, being shown as inwardly bent ribs, the ribs 44 extending outwardly preferably beyond the 10 walls of the ribs 45, 46.

The ribs follow the cross-sectional contour of the shell and form strengthening means for supporting the carton and for handling the same, and aid in maintaining 15 the cylindrical forms for the sections of the carton and avoid undue shock to the eggs. These advantages are obtained by the outwardly extending ribs 44 and enhanced by the inwardly extending ribs 45, 46, and form 20 a cushion for the carton and the eggs contained therein.

Any number of the ribs 44, 45, 46, may be employed, for spacing of the same lengthwise of the carton.

25 The flanges 28, 29, are preferably pasted to the semi-cylindrical sections 12, 14, along the inside faces of the walls of said semi-cylindrical sections and at both sides of the inner grooves formed by the outwardly extending ribs 44, and at both sides of the inwardly extending ribs 45, 46, as will be clearly seen in Figs. 1 and 3, whereby the ribs are reenforced and the carton additionally strengthened, especially in lengthwise 30 direction.

Suitable closing means are provided for the carton, shown as a string 51, one end of which is secured to a fastening clip 52, which fixes a button 53 to the carton, the 40 string being received around the carton, and the other end of the string being wound around said fastening clip under the button.

Having thus fully described my invention, what I claim as new, and desire to secure by 45 Letters Patent, is:

1. An egg carton comprising a shell embodying a pair of substantially semi-cylindrical sections forming shell-halves hinged together by a score integral in said shell at one side of said substantially semi-cylindrical sections, egg-nest sections extending laterally from the opposite sides of said respective shell-sections toward said score and provided with mating egg-pockets, the bodies of said substantially semi-cylindrical sections provided with radially outwardly extending ribs forming grooves at the inner surfaces of said substantially semi-cylindrical sections, said ribs extending about said substantially semi-cylindrical sections adjacent to the ends thereof for strengthening the substantially semi-cylindrical forms of said sections and resiliently spacing the intermediate portions 60 of said substantially semi-cylindrical sec-

tions between said ribs from a plane surface upon which said carton may be placed, and the wall portions of said substantially semi-cylindrical sections between said ribs provided with inwardly extending indentations 70 in axial lines with said egg pockets, and constructed and arranged for cushioning the eggs by the conjoint action of said inwardly extending indentations and the wall portions in which said indentations are contained being spaced from said plane surface, whereby said eggs are individually and collectively cushioned.

2. An egg carton comprising a shell embodying a pair of substantially semi-cylindrical sections forming shell-halves hinged together by a score integral in said shell at one side of said substantially semi-cylindrical sections, egg-nest sections extending laterally from the opposite sides of said respective shell-sections toward said score and provided with mating egg-pockets, the bodies of said substantially semi-cylindrical sections provided with radially outwardly extending ribs forming grooves at the inner surfaces of said substantially semi-cylindrical sections and with radially inwardly extending ribs, said ribs extending about said substantially semi-cylindrical sections for strengthening the substantially semi-cylindrical forms of said sections, and flanges extending from the edges of said respective egg-nest sections at said score, said flanges pasted to the inside faces of the side walls of said substantially semi-cylindrical sections adjacent to said score at both sides of said ribs and groove, said ribs and said pasting of said flanges at the respective sides thereof strengthening the substantially semi-cylindrical form of said sections and the forms of said ribs lengthwise of said sections, and said radially outwardly extending ribs arranged to support said carton with the body of said carton spaced 90 from a plane surface on which said carton 95 may be placed.

3. An egg carton comprising a shell formed with a plurality of pairs of substantially semi-cylindrical sections to form shell-halves hinged together by a score integral in said shell, egg-nest sections extending laterally from said respective shell-sections toward said score and provided with mating egg-pockets, the outer portions of said substantially semi-cylindrical sections of said shell provided with inwardly extending indentations in axial lines with said egg-pockets for cushioning the respective ends of the eggs therein, and the ends of said shell provided with radially outwardly extending ribs extending about said substantially semi-cylindrical sections for strengthening the substantially semi-cylindrical forms of said sections and for supporting said carton with the body of said carton 100 105 110 115 120 125 129

- spaced from a plane support on which said carton may be placed, flanges extending from the edges of said egg-nest sections at said score pasted to the inner faces of the 5 walls of said substantially semi-cylindrical sections adjacent to said score and at both sides of said ribs, whereby to strengthen the forms of said substantially semi-cylindrical sections and ribs.
- 10 4. An egg carton comprising a shell embodying a pair of substantially semi-cylindrical sections forming shell-halves hinged together by a score integral in said shell at one side of said substantially semi-cylindrical sections, egg-nest sections extending laterally from the opposite sides of said respective substantially semi-cylindrical sections toward said score and provided with mating egg-pockets, the bodies of said substantially semi-cylindrical sections provided 15 with radially outwardly extending projections forming indentations at the inner surfaces of said substantially semi-cylindrical sections, said projections extending about said substantially semi-cylindrical sections, and flanges extending from the edges of 20 said respective egg-nest sections at said score along the inside faces of the side walls of said substantially semi-cylindrical sections adjacent to said score and complementary to said projections for strengthening 25 the substantially semi-cylindrical form of said sections, and said radially outwardly extending projections arranged to support said carton with the body of said carton spaced from a plane surface on which said 30 carton may be placed.
- 15 5. An egg carton comprising a shell embodying a pair of substantially semi-cylindrical sections forming shell-halves hinged together by a score integral in said shell at one side of said substantially semi-cylindrical sections, egg-nest sections extending laterally from the opposite sides of said respective substantially semi-cylindrical sections toward said score and provided with mating egg-pockets, the bodies of said substantially semi-cylindrical sections provided 20 with radially outwardly extending projections forming indentations at the inner surfaces of said substantially semi-cylindrical sections, said projections extending about said substantially semi-cylindrical sections, and flanges extending from the edges of 25 said respective egg-nest sections at said score along the inside faces of the side walls of said substantially semi-cylindrical sections adjacent to said score and complementary to said projections for strengthening 30 the substantially semi-cylindrical form of said sections, and said radially outwardly extending projections arranged to support said carton with the body of said carton spaced from a plane surface on which said 35 carton may be placed.
- 20 In testimony whereof, I have hereunto signed my name.
- ERICH SCHINSCHOLL.
